UNITED STATES PATENT OFFICE.

FEDOR E. DECKERT AND OSCAR ROBERT DECKERT, OF SYRACUSE, NEW YORK,
ASSIGNORS TO THE PROSPERITY CO. INC., OF SYRACUSE, NEW YORK, A COR-
PORATION OF NEW YORK.

GARMENT-PRESSING MACHINE.

Application filed October 28, 1919. Serial No. 333,908.

To all whom it may concern:

Be it known that we, FEDOR E. DECKERT and OSCAR ROBERT DECKERT, citizens of the United States, and residents of Syracuse, in the county of Onondaga and State of New York, have invented a certain new and useful Garment-Pressing Machine, of which the following is a specification.

This invention relates to garment pressing machines and has for its object particularly simple and efficient means for operating the pressing head and one of the objects of the invention is the particularly simple and efficient means for limiting the movement of the toggle levers. Another object is means for raising the pressing head and another object, means for locking the pressing head in its down position.

The invention consists in the novel features and in the combinations and constructions hereinafter set forth and claimed.

In describing this invention, reference is had to the accompanying drawings in which like characters designate corresponding parts in all the views.

Figure 1 is a side elevation of a pressing machine embodying our invention.

Figure 1^a is a fragmentary plan view of the rear arm of the lever carrying the pressing head.

Figures 2 and 3 are respectively, enlarged side elevations of the joint of the toggle levers and contiguous parts, Fig. 2 showing the position of the parts when the toggle is in its extended position, and Fig. 3 the position of the parts when the toggle levers are in their folded position.

Figure 4 is a rear elevation of parts seen in Fig. 2.

Figures 5 and 6 are respectively a fragmentary plan view and elevation of the operating lever for the toggle and contiguous parts.

This pressing machine comprises, generally, a frame 1, a lower buck 2 mounted on the frame, a pressing head 3 movable toward and from the buck 2, a lever 4 pivoted at 5 between its ends to the frame and carrying the pressing head on the front arm thereof, and means for operating the lever 5 connected to the rear arm thereof.

The frame 1, buck 2, pressing head 3, and lever 4 may be of any suitable form, size and construction.

The means for operating the lever 4 comprises toggle levers pivoted respectively to the frame and to the rear arm 6 of the supporting lever 4 and tending to normally operate said lever 4 to raise the pressing head 3 and fold the toggle levers and means for locking the operating means in its position occupied when the toggle is extended and the pressing head 3 pressed against the buck 2 or the garment thereon.

7 and 8 are respectively the levers or links of the toggle which are pivoted together at 9, the lever 7 being pivoted to the lower end of the frame at 10 and the lever 8 being pivoted at 11 to the rear arm 6 of the lever 4 supporting the pressing head 3.

The lever 7 has a forwardly extending extension 12 which constitutes a foot lever, said foot lever terminating in the pedal 13 at its front end. The lever or link 8 comprises a bracket 14 having bearings on the pivot 9 connecting the levers, a rod 15 connected to the bracket 14 at its lower end and threading at its upper end into a bearing or bracket 16 mounted on the pivot 11.

The toggle is lengthened or shortened by turning the rod 15 into or out of the bracket 16 and the turning of the rod is effected by means of a hand wheel 17 mounted on the rod 15 and having its hub 18 abutting against the lower face of the bracket 14 and against a bushing 19 on the rod above the hub 18, the bushing being held from endwise movement by a split clamp 20 threading on the rod. It is clamped onto the rod 15 by a screw 21.

The wheel 17 and hence the rod 15 is held from turning by means of a spring pressed bolt 22 arranged in the bracket 14 and co-acting with spokes of the wheels 17, this bolt being depressible against the action of its spring by a suitable handle 23.

The toggles 7 and 8 are provided with means for limiting the folding movement of the toggle and also the extending movement hereof and as here shown one of the toggle levers as the lever 8 or the bracket 14 thereof is provided with arms 24, 25 located in front

and in the rear of the toggle joint or pivot 9, the arm 25 at the rear of said joint extending downwardly and being opposed to the portion of the lever 7 directly below the joint 9 and provided with means for engaging said lever when the toggle is in its extended position.

The arm 24 moves into engagement with the front side of the lever 7 to a point directly 10 below the joint 9 when the toggle is in its folded position as shown in Fig. 3. Usually, the lever 7 is provided with a buffer extending therethrough and having heads exposed on the front and rear sides of the lever, this 15 buffer being also adjustable edgewise.

26 designates the buffer which threads into the lever 7 and has a head 27 on the rear side thereof for receiving a wrench and also has a buffer 28 on the front side thereof for 20 contacting the end of the arm 24, the head 28 being usually rubber or some other yielding material.

The means provided on the arm 25 for 25 contacting the lever 7, as here shown, includes a screw 29 extending forwardly and rearwardly through the lower end of the arm 25 and having a handle or wheel 30 at its rear end. The screw 29 is held in its adjusted position by a suitable lock nut 31.

30 The buffer 26 is adjusted to limit the opening movement of the toggle when a presser head reaches a predetermined height and the screw 29 is adjusted to limit the closing or extending movement of the toggle before 35 the joint of the toggle passes through the dead center line of the toggle so that upon releasing of the operating lever 12 the pressing head will rise. The pressure of the toggle can also be regulated by lengthening or 40 shortening the link 8 by turning the hand wheel 17.

The means for raising the pressing head 3 in this embodiment of our invention comprises a suitable weight 32 acting on the rear 45 arm of the lever 6, it being here shown as mounted on the pivot 11 and having forwardly extending arms 33 pressing upwardly on the rear arm 6 of the supporting lever 4 or the pressing head 3.

50 The means for raising the supporting lever 4 also comprises a spring 34 connected at 35 its lower end to the frame and at its upper end to the rear arm 6 of the lever 4.

The connection or coupling between the 55 spring and the rear arm being adjustable lengthwise of said arm in order to vary the lifting effect.

As here shown, (Figs. 1 and 1^a) the rear arm of the lever is formed with a lengthwise 60 slot 36 and with alined notches or seats 37 on opposite sides of the slot and the spring is provided at its upper end with a rod 38 extending through the slot 36 and through a bearing 39 having laterally extending arms 65 40 which seat in any two of the alined

notches 37 on opposite sides of the slots 36.

The rod 38 is threaded at its upper end and a nut 41 threads on said rod against the upper face of the bearing 39. Hence, the tension of the spring can be adjusted by 70 turning the nut 41 and the effective leverage of the spring on the arm 6 can be adjusted by moving the bearing 39 forwardly or rearwardly of the arm 6. In some instances, the operator when using the machine 75 merely depresses the foot pedal 30 and releases the same and in other times holds the presser head 3 in its down position on the garment and also when the machine is idle the presser head 3 is held onto the buck 80 2 for the purpose of keeping the buck 2 and presser head 3 warm, it being understood that the buck and head are hollow and that the heating medium as steam is passed therethrough.

85 Means is provided for locking the pressing head 3 in its depressed position against the action of the weight 32 and the spring 34 tending to lift the pressing head. This means comprises a latch 42 pivoted at 43 90 to a bracket on the upper side of the operating lever 12 and depending from the bearing of the pivot and also having a horizontally extending weighted arm 45 extending rearwardly therefrom, the latch coacting with 95 the locking member or keeper 46 fixed to the foot of the frame 1.

The latch 45 is movable from its position shown in Fig. 1 upwardly about the pivot 43 into the position indicated by dotted lines 100 in Fig. 1 and when in the position shown in dotted lines it is permanently out of operative position.

When however, it is desired to lock the 105 pressing head in its depressed position the latch 45 is swung on its pivot from its dotted line position into its full line position, Fig. 1 where upon depression of the pedal 13, it will latch into engagement with the keeper 46. It is moved out of engagement with the keeper 46 by means of a lever 47 pivoted between its ends at 48 to the pivot of the frame 1, the rear arm of the lever having a head 49 thereon movable into engagement 110 with the under side of the weighted arm 45 of the latch 42. The front arm of said lever 47 is provided with a suitable pedal.

When the pedal 47 is depressed, obviously, 115 the head 49 will be moved upwardly and move the latch 42 on its pivot to disengage the latch from the keeper 46.

A suitable spring 50 is connected at one end to the lever 12 and at its other end to the frame 1 tending to move the pedal lever 12 upwardly and hence the toggle rearwardly and acting in conjunction with the spring 34 to open the toggle and lift the presser head 4.

In operation, the screw 26 of the buffer 120 of the lever 7 is adjusted to position the 130

- head 28 in proper position to limit the upward movement of the pressing head 3 and the screw 29 adjusted to engage the lever 7 prior to the time the joint of the toggle 5 passes into or through the dead center line of the toggle joint 9, the link 8 being shortened or extended to effect the positioning of the toggle joint 9 when the toggle is in its extended position.
- 10 The seat 39 of the spring 34 is lengthwise adjusted to the proper position lengthwise of the rear arm 6 of the supporting lever 4 so that the machine can be operated with a minimum effort.
- 15 Owing to the lengthwise adjustment of the link 8, the adjustment of the parts 26 and 29 and the adjustment of the spring 34 along the rear arm 6 of the supporting lever 4 for the presser head 3 the machine can be 20 adjusted to operate with the maximum pressure and with minimum effort on the part of the operator and further readily opens when the pedal lever 12 is released.
- What we claim is:
- 25 1. A toggle for garment pressing machines comprising toggle levers pivoted together, one of said levers being formed with an arm located at one side of the toggle joint in the path of movement thereof and the other lever 30 being formed with a buffer adjustable transversely thereof for coacting with said arm to limit the movement of the toggle joint in one direction, substantially as and for the purpose described.
- 35 2. A toggle for garment pressing machines comprising toggle levers pivoted together at like ends, one of the levers being provided with arms located in front and in the rear of the joint of the toggle, one being movable 40 into engagement with the other lever when the toggle is extended and the other being movable into engagement with said lever when the toggle is folded, one of the arms being provided with an adjustable 45 member for coacting with said lever, substantially as and for the purpose set forth.
3. A toggle for garment pressing machines comprising toggle levers pivoted together, one of the levers being formed with arms located in front and in the rear of the toggle joint and the other lever being provided with a buffer adjustable transversely thereof for coacting with one of said arms, and the other of said arms being provided with an
- adjustable member for coacting with the lever on which the buffer is provided, substantially as and for the purpose described.
4. A toggle for garment pressing machines comprising toggle levers pivoted together, one of the levers being provided with a forwardly and rearwardly adjustable stop located near the toggle joint and the other lever being provided with an arm movable into engagement with the stop, substantially as and for the purpose specified.
5. In a garment pressing machine, the combination of a frame, a buck supported on the frame, a pressing head movable toward and from the buck, a supporting lever for the pressing head pivoted between its ends 70 to the frame and carrying the head on the front arm thereof, means for operating the lever connected to the rear arm thereof, the rear arm of the lever being provided with a series of seats extending lengthwise thereof, a coupling adjustable in any one of said seats, and a spring connected at one end to the frame and at its other end to the coupling, substantially as and for the purpose described.
6. In a garment pressing machine, the combination of a frame, a buck supported on the frame, a pressing head movable toward and from the buck, a supporting lever for the pressing head pivoted between 85 its ends to the frame and carrying the head on the front arm thereof, means for operating the lever connected to the rear arm thereof, the rear arm of the lever being formed with a slot extending through its upper and lower faces and with a series of 90 seats arranged on opposite sides of the slots, a coupling extending across the slot and having means engaging the seats and adjustable from one set of seats to another 95 lengthwise of said arm, and a spring connected at one end to the frame and at its other end to said coupling, the connection between the spring and the coupling extending through the slot, substantially as 100 and for the purpose specified.
- In testimony whereof, we have hereunto signed our names at Syracuse, in the county of Onondaga, and State of New York, this 1st day of July, 1919.

FEDOR E. DECKERT.
O. ROBERT DECKERT.
